SYNCHRONIZING DEVICE

Judge D. Hitchcock, United States Army,
Atlanta, Ga.

Application January 15, 1946, Serial No. 641,360

4 Claims. (Cl. 178—53.1)

(Granted under the act of March 3, 1883, as
amended April 30, 1928; 370 O. G. 757)

1

The invention described herein may be manufactured and used by or for the Government for governmental purposes, without the payment of any royalty thereon.

This invention relates to teletypewriter apparatus, and more particularly to improvements in typing reperforators used in connection with such apparatus.

In reperforators, for some reason, it often happens that the normal start and stop impulses do not arrive at the selector magnets at the proper time; and it has been necessary to produce artificial start and stop impulses somewhat shorter than normal start and stop impulses and to superimpose these artificial impulses on to but within the limits of the normal start and stop impulses in such a way as to control the selector magnets. The production of the artificial start and stop impulses have heretofore been accomplished by an electronic apparatus having seven relays with associated resistors, condensers, etc., which apparatus is objectionable because it is complicated and expensive.

It is, therefore, an object of this invention to provide a mechanical synchronizer for a reperforator to produce artificial start and stop impulses. The mechanical synchronizer is simpler, cheaper, more compact and more reliable than the electronic apparatus heretofore used for the same purpose. The mechanical synchronizer hereinafter described will satisfactorily perform any and all functions performed by the seven relays it is designed to replace. It will also not only assure that the same number of characters are perforated as were transmitted, but will decrease the number of errors on any message received by radio teletype when errors are caused by imperfect radio reception.

The above and other objects are attained by the novel arrangement and construction hereinafter described and illustrated by the accompanying drawings, forming a part hereof, and in which:

Fig. 1 is an elevational view of a mechanical synchronizer embodying the invention.

Fig. 2 is an elevational view of a start cam and start contacts.

Fig. 3 is an elevational view of a stop cam and stop contacts.

Fig. 4 is a schematic wiring diagram of the apparatus.

Fig. 5 is a schematic diagram of a clutch release circuit.

Fig. 6 is a perspective view of the selector cam sleeve of a standard typing reperforator as used with this invention.

Referring to Fig. 4, the stop contacts 1 and 2 are connected to the armature 3 and to the mark contact of a receive relay 6 so that when the stop contacts are closed they close the selector

2

magnet circuit even if the receive relay is in a spacing condition.

The start contacts 4 and 5 are connected in series with the receive relay armature 3 and selector magnets 7 so that when they open, the selector magnet circuit is open even if the receive relay is in a marking condition.

The synchronizer is mounted on the base of a reperforator and is supported by a bracket 17 provided with a bearing 18 in which is journalled a cam sleeve shaft 8, to which is fixed a cam sleeve shaft gear 9. A cam sleeve 10 is mounted on one end of the cam sleeve shaft and is driven by two friction clutches 20 and 21. Fixed to the cam sleeve are the stop cam 22, start cam 23, and stop arm 24.

Mounted on release bracket 13 is release lever 11 controlled by release magnets 12, also mounted on release bracket 13. A stop contact lever 15 actuated by the stop cam controls the stop contacts 1 and 2 and a start contact lever 16 controls the start contacts 4 and 5. (See Figs. 1, 2, and 3).

As stated above the mechanical synchronizer is an attachment designed to replace a number of relays of the usual electronic synchronizer, and is mounted so that cam sleeve shaft gear 9 is actuated by a gear on the reperforator base which in turn is actuated by a gear on the reperforator.

Figure 6 shows the selector cam sleeve 45 of a main shaft 44 of a standard typing reperforator. Machines of this type are manufactured by the Teletype Corporation of Chicago, Illinois, under model number FPR 5H193 (other types, not appreciably different are the FPR 23 series). A detailed description of these machines will be found in Bulletin No. 171, Issue 1, May 1941, Teletype Corporation, Chicago, Illinois.

In operation, assuming that the typing reperforator is in operation, the following sequence of operation starts just before the clutch throwout lever 43 operates the clutch lever contacts 30, 31 also on the reperforator (Fig. 5). At this time the release magnets 12 are deenergized, the release lever 11 is held in its downward position by a spring, the stop arm 24 is resting against the release lever 11, the cam sleeve is standing still and the stop contact lever 15 and start contact lever 16 are resting on the high part of their respective cams. The stop contacts 1 and 2 are open and the start contacts 4 and 5 are closed.

The clutch throwout lever 43 of the reperforator closes the clutch lever contacts 30, 31, the release magnets 12 are energized, and operates the release lever 11 upward, which releases the release stop arm 24. The cam sleeve starts rotating, and stop contact lever 15 rides into the indent 41 of stop cam 22. The stop contacts 1, 2 close, starting the stop impulse; the clutch lever contacts 30, 31 then open and the release magnets

12 are de-energized, and the release lever 11 is pulled to a downward position by a spring. The stop contact lever 15 then rides onto the high part of the stop cam 22 and opens the stop contacts, and the stop impulse ends.

The start contact lever 16 then rides into indent 42 of start cam 23 and the start contacts 4, 5 open, starting the start impulse. Start contact lever 16 rides on the high part of start cam 23 and the start contacts close, ending the start impulse. The cam sleeve continues to rotate until stop arm 24 strikes against the release lever 11, when the cam sleeve 10 stops rotating and stands still until the release magnets 12 are again energized.

What is claimed is:

1. A synchronizing device for a teletypewriter reperforator, comprising a shaft, a start cam and a stop cam mounted on the shaft, a receive relay having a marking and spacing condition, a selector magnet circuit, stop contacts controlled by the stop cam so that they close the selector magnet circuit even if the receive relay is in a spacing condition, and start contacts controlled by the start cam so that they open the selector magnet circuit even if the receive relay is in a marking condition.

2. A synchronizing device for a teletypewriter reperforator, comprising a shaft, means to rotate the shaft, a receive relay having a marking and spacing condition, a selector magnet circuit, stop contacts, a stop cam mounted on the shaft to control the stop contacts so that they close the selector magnet circuit even if the receive relay is in a spacing condition, start contacts, and 35

a start cam mounted on the shaft to control the start contacts to open the selector magnet circuit even if the receive relay is in a marking condition.

3. A synchronizing device for a teletypewriter reperforator, comprising a shaft, a receive relay having an armature with a spacing and marking condition, a selector magnet circuit, a stop cam and a start cam mounted on the shaft, means to rotate the shaft, a stop arm to prevent rotation of the cams, a release magnet adapted to move the stop arm to enable the cams to rotate, start contacts in series with said armature and selector magnet circuit, so that the selector magnet circuit will be open even if the receive relay is in a marking condition, and stop contacts connected to the armature and mark contact of the receive relay to close the selector magnet circuit even if the receive relay is in a spacing condition.

4. In a synchronizing device for a teletypewriter reperforator, a shaft means to rotate the shaft, a stop cam and a start cam on the shaft, stop contacts controlled by the stop cam, start contacts controlled by the start cam, a stop arm to prevent rotation of the cams, a release magnet adapted to move the stop arm to a position to enable the cams to rotate, said stop contacts and a receive relay having an armature and at least a mark contact, said start contacts being in series with said armature, and the stop contacts being in parallel with the armature and mark contact.

JUDGE D. HITCHCOCK.
